[57] ABSTRACT

A golfer's training aid including a base, a vertical post and an elongated horizontal member extending outward from the post. The horizontal member includes a collar at one end and a golf ball sighting member at the other end. A bend is provided in the horizontal member adjacent the collar, whereby the collar frictionally engages the post to maintain the sighting member in a plane at a right angle to the post. The sighting member may be in the form of a loop of wire or a solid disc. The sighting member is positioned over a golf ball during the execution of a golf club swing.

GOLFER'S PRACTICE AID

SUMMARY OF THE INVENTION

This invention relates to a golfer's practice aid to assist a golfer in practicing proper tee and fair-way strokes using the appropriate club and a golf ball or practice ball.

One of the most common faults of the average golfer is in moving the head during the golf swing. Use of the invention enables the golfer to maintain a steady head position during the swing thus reducing body sway and assisting the development of proper rhythm of movement in the back and forward swing.

IN THE DRAWING

FIG. 1 is an elevational view of a golfer's practicing aid embodying the principles of the present invention;

FIGS. 2 and 3 are plan and side views, respectively, on an enlarged scale, of the sight piece of FIG. 1; and

FIGS. 4 and 5 are plan and side views, respectively, of a modified sight piece.

The assembled device includes a base 10, a post 12 and a sight piece 14. The base 10 may be made from plastic, hollowed out with baseweights inserted. The base may be, for example, 5 inches long by 2 $\frac{3}{4}$ inches wide by 1 $\frac{1}{4}$ high. The post 12, which is secured at its lower end to the base 10, may be a length of 8 or 10 gauge wire 8 to 10 inches long and coated with plastic.

The sight piece may be made of a length of 10 gauge wire 10 to 12 inches long and carrying a punched-out disk 16 or collar at one end and a wire loop 18 at its other end. The loop may have an inside diameter of 1 $\frac{1}{2}$ to 2 inches, and the disk may be five-eighths inches in diameter with a $\frac{1}{4}$ inch hole in its center. The entire sight piece 16 is coated with plastic to a thickness which will give the disk 16 a locking action on the post 12 when the disk 16 is titled.

The locking action between the disk 16 and the post

12 is aided by bending the wire three-fourths to 1 inches from the disk 16 so that in the tilted position of the disk 16 the loop 18 will be parallel to the ground. With this arrangement the sight piece 14 can revolve about the post 12 if struck by the golf club.

In use the assembly is placed to one side of a golf ball 20, and the golfer stands on the other side of the ball 20 and sights the ball 20 in the loop 18.

The sight piece 14' of FIGS. 4 and 5 is the same as in FIGS. 1-3 except that the outer end is provided with a solid sighting disk 22 which is of smaller diameter than the ball 20.

It is not essential for the parts to be made separate, and the device can be made in one or two pieces. However, separation of the sight piece from the post allows the former to swivel if struck by a golf club and thus avoids damage to the clubs.

What is claimed is:

1. A golf practice aid comprising:

- a. an upright post secured at one end thereof to a base; and
- b. a horizontal sight piece having a collar at one end and a circular golf ball sighting member at the other end thereof, said collar being directly disposed over and contacting said post so as to be releasably located thereon and slideable along said post,

a bend provided intermediate said sighting member and said collar so that interior portions of said collar frictionally engage said post, thereby causing said sighting member to lie in a plane at substantially a right angle to said post, and the height of said post being such that said sighting member may be moved to a position above a golf ball during the execution of a golf club swing for sighting on said golf ball.

2. A golf practice aid as in claim 1 wherein said sight piece and post are constructed of stiff wire coated with plastic.

3. A golf practice aid as described in claim 1 wherein said sighting member is a solid disk.
